United States Patent Office

Des. 227,207
Patented June 12, 1973

227,207

CHAIR

Don Ray Gill, Hammond, Ind., assignor to Mohasco
Industries, Inc., Amsterdam, N.Y.

Filed Apr. 22, 1971, Ser. No. 136,636

Term of patent 14 years

Int. Cl. D6—02

U.S. Cl. D6—71

FIG. 1.

FIG. 2.

FIG. 1 is a perspective view of a chair illustrating my new design.

FIG. 2 is an enlarged fragmentary view showing a portion of one of the insert arm-panels in greater detail.

The back of the chair is conventionally plain while the side not shown is substantially identical to the side shown.

I claim:

The ornamental design for a chair, as shown and described.
